THOMAS D. WORKMAN, OF GENESEO, KANSAS

GRADER BLADE HOIST

Application filed April 7, 1931. Serial No. 528,428.

This invention relates to hoists for blades of road graders.

A primary object of the invention is to provide a hoist for raising and lowering road grader blades and the like which is so constructed that the blade may be quickly raised or lowered with a minimum amount of effort on the part of the operator.

Another object is to provide a double acting hoist of this character to facilitate the lowering and raising operation.

In carrying out these objects, the invention is susceptible of a wide range of modification without departing from the spirit or sacrificing any of the advantages of the claimed invention; there being shown in the drawings for illustrative purposes a preferred and practical form, in which:

Figure 1 represents a side elevation of a road grader equipped with this improved hoist;

Fig. 2 is a top plan view thereof;

Fig. 3 is an enlarged vertical section of the hoist with parts being broken out for convenience in illustration;

Fig. 4 is a side elevation of the upper portion of the hoist with parts broken off;

Fig. 5 is a transverse section taken on the line 5—5 of Fig. 3 with the upper portion of the gear housing broken away to disclose the interior; and

Fig. 6 is a transverse section taken on the line 6—6 of Fig. 3.

The hoist 10 which constitutes this invention is shown applied to a conventional road grader which includes the usual supporting front wheels 1 and caterpillar rear construction 2 with an arched frame 3 from the front portion of which extends rearwardly blade supporting bars 4 which diverge toward their rear ends and are connected with the scraping blade 5 which is designed to be raised or lowered by the hoist 10 in a manner presently to be described.

A cross bar 6 is arranged transversely above the frame 3 and supports the hoist constituting this invention. The lower end of the hoist is connected by a universal joint with the circle 7 attached to the blade 5. It is to be understood that there are two of these

hoists transversely spaced from each other as shown in Fig. 2 by means of which one end or the other of the blade may be raised at will or the blade bodily raised uniformly by operating both hoists. In view of the fact that they are exactly alike one only will be described in detail.

Each hoist 10 includes a worm gear casing 11 in which a worm gear 20 is revolvably mounted and protected by said casing against the weather. Extending from the upper face of the casing 11 is a hollow pipe 12 the inner face of which is made angular to receive a correspondingly shaped angular pipe 13 connected by a universal joint 14 with the bar 6. This angular connection of the two pipes 12 and 13 provides for their longitudinal telescopic movement and yet prevents turning of the unit, of which they constitute a part.

Extending from the lower wall of the casing 11 is another pipe 15 which aligns with the pipe 12 and is made circular in configuration to receive the correspondingly shaped pipe 16 connected by a universal joint 17 with the blade carrying member 7. The interior of the pipes 13 and 16 are threaded to receive left and right hand threaded shafts 18 and 19 which are made integral with the worm gear 20 and rotate therewith without contacting the pipes 12 and 15.

A worm carrying shaft 21 is journalled in the casing 11 as shown clearly in Fig. 5 and the worm meshes with the worm gear 20 so that when the shaft 21 is rotated the worm gear will be driven. One end of the shaft 21 projects beyond the casing 11 and is connected by a universal joint 22 with an angular rod 23 telescoped into a correspondingly shaped pipe 24 which is connected by a universal joint 25 with a shaft 26 mounted in a bearing 27 and having an operating wheel 28 thereon. This wheel 28 is positioned in the cab of the grader for convenient operation by the operator.

It will thus be seen that when the wheel 28 is rotated the worm 21 will be similarly turned and meshing with the worm gear 20 will drive said gear and thus operate the threaded shafts 18 and 19 causing the pipes 13 and 16 to move inwardly in pipes 12 and 13.

15 and thus raise the blade 5. It is of course understood that turning of the wheel in the opposite direction will reverse the movement of these parts and lower the blade.

6 The portion of the casing 11 in which the shaft 21 is journalled has a removable cap 11a to afford access to the interior of the casing and to permit the parts to be assembled.

It will thus be seen that this double acting 10 worm gear will by a single turn of the wheel 28 raise or lower the blade 5 twice the distance which could otherwise be done.

Without further description it is thought 15 that the features and advantages of the invention will be readily apparent to those skilled in the art, and it will, of course, be understood that changes in the form, proportion and minor details of construction may be resorted to, without departing from the 20 spirit of the invention or its scope as claimed.

I claim:

1. A double acting hoist for grader blades and the like comprising a gear casing having tubular members extending from opposite 25 faces thereof in longitudinal alinement, pipes telescopically engaged with said members and having universal joints at their ends provided with connectors for uniting said ends to a support and the object to be raised and lowered, said tubes being internally threaded, a worm gear mounted in said casing and having right and left hand threaded 30 shafts extending from its opposed faces and threaded into said tubular pipes, a worm 35 meshing with said gear, and means for operating said worm for projecting and retracting said tubular members.

2. A double acting hoist for grader blades and the like comprising a gear casing having 40 tubular members extending from opposite faces thereof in longitudinal alinement, pipes telescopically engaged with said members and having universal joints at their ends provided with connectors for uniting said ends 45 to a support and the object to be raised and lowered, said tubes being internally threaded, a worm gear mounted in said casing and having right and left hand threaded shafts extending from its opposed faces and threaded 50 into said tubular pipes, a worm meshing with said gear, means for operating said worm for projecting and retracting said tubular members, one of said tubular members and one of the pipes carried by said 55 casing having sliding but non-rotatable engagement.

THOMAS D. WORKMAN.
